SUCKER ROD RACK

Roy Albert Roberts, Bakersfield, Calif.

Application May 11, 1939, Serial No. 273,141

1 Claim. (Cl. 211—70)

The present invention relates to new and useful improvements in sucker rod racks particularly for oil wells and has for its primary object to provide, in a manner as hereinafter set forth, a device of this character which may be expeditiously suspended from a derrick and which may be rotated to facilitate the mounting thereon and removal therefrom of the sucker rods.

Another very important object of the invention is to provide a rack of the aforementioned character which will facilitate the removal of the sucker rods in the reverse order in which they are placed thereon thereby assuring that each rod will be in its former place when put back in the well.

Other objects of the invention are to provide a sucker rod rack of the character described which will be comparatively simple in construction, strong, durable, highly efficient and reliable in use, compact, portable and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view partially in side elevation and partially in vertical section, showing a sucker rod rack constructed in accordance with the present invention, the section being taken substantially on the line 1—1 of Fig. 2.

Figure 2 is a horizontal sectional view, taken substantially on the line 2—2 of Fig. 1.

Referring now to the drawing in detail, it will be seen that the embodiment of the invention which has been illustrated comprises a vertical shaft 1 of suitable metal which is adapted to be suspended from an oil well derrick through the medium of a hook 2 on the upper end of said shaft. The hook 2 is provided with a latch 3. The lower end portion of the shaft 1 is threaded, as at 4.

Mounted for rotation on the shaft 1 is a metallic sleeve or barrel 5. Bearings 6 are provided in the end portions of the barrel 5. A nut 7 is threaded on the lower end portion 4 of the shaft

1 for retaining the barrel 5. A cotter pin 8 secures the nut 7.

Fixed on the lower portion of the barrel 5 is an inverted conical support 9. The support 9 has formed therein a plurality of radial slots 10 for the reception of the sucker rods. The flat or horizontal base portion 11 of the inverted conical support 9 has formed therein, on opposite sides of the slots 10, complementary recesses constituting seats 12 for the reception of the sucker rods.

It is thought that the manner in which the rack functions will be readily apparent from a consideration of the foregoing. If desired, the rod receiving slots 10 may be consecutively numbered. The device is suspended from the derrick through the medium of the hook 2 and the sucker rods, as they are pulled, are placed consecutively in said slots. That is, a rod is placed in the first slot, the second rod is placed in the next slot, etc. Of course, the support 9 is rotated to bring the slots 10 into position to facilitate the placing of the sucker rods therein. When the rods are to be replaced in the well the foregoing operation is simply reversed. Thus, each section of the rod will occupy its former place in the 25 string.

It is believed that the many advantages of a sucker rod rack constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

A sucker rod rack comprising a vertical shaft, a suspension hook on the upper end of said shaft, anti-friction bearings on the upper and lower portions of the shaft, a barrel journaled on said bearings, a nut threaded on the lower end portion of the shaft for retaining the bearings and the barrel in position on said shaft, and a substantially conical, hollow metallic support fixed on the barrel and having a plurality of radial slots therein for the reception of sucker rods.

ROY ALBERT ROBERTS.
